UNITED STATES PATENT OFFICE

168,496

BASEBALL GLOVE

Theodore B. Blepp, Fairview Park, Ohio

Application April 16, 1952, Serial No. 19,354

Term of patent 14 years

(Cl. D3—11)

To all whom it may concern:

Be it known that I, Theodore B. Blepp, a citizen of the United States, residing at Fairview Park, in the county of Cuyahoga and State of Ohio, have invented a new, original, and ornamental Design for a Baseball Glove, of which the following is a specification, reference being had to the accompanying drawing, forming part hereof.

Fig. 1 is a perspective front view of a baseball glove showing my new design;

Fig. 2 is a perspective rear view of the baseball glove shown in Fig. 1.

I claim:

The ornamental design for a baseball glove, substantially as shown.

THEODORE B. BLEPP.
